Application February 28, 1949, Serial No. 78,869

6 Claims. (Cl. 255—1.8)

1

This invention relates to diamond drilling operations and the principal object of the invention is to provide a method and apparatus for establishing a complete length of casing for shielding and guiding the drill rods through overburden from the surface to bed rock in locations where the nature or depth of the overburden prevents the usual stand pipe from being driven.

A further important object is to provide a method and apparatus which will enable the casing to be easily and expeditiously sunk to bed rock by utilizing the equipment used for drilling without requiring any additional expensive or cumbersome machinery which would be difficult to transport or handle.

The principal feature of the invention resides in operating a casing-enclosed diamond drill within a stand pipe driven as far as possible into the overburden to advance both the drill and enclosing casing, provided with a casing bit through the overburden to bed rock by providing special fittings to lock the casing to the drill to rotate and advance therewith.

A further and very important feature consists in providing fittings for locking the drill rod to its enclosing casing, which fittings can be readily removed from the surface after the casing has been advanced to bed rock to permit the drill to be thereafter operated freely within the casing to penetrate the bed rock.

A still further feature consists in forming the fittings as interengaging socket connections which can be readily attached to standard casing and drill rods to enable the sinking of the casing through the overburden to be accomplished by means of standard drilling equipment.

Referring to the accompanying drawings,

Figure 1 is a part-elevational part-sectional view showing a string of drill rods and enclosing casing in position within the stand pipe ready to begin the advance of the casing through the remaining overburden and showing the manner in which the drill rod string is locked to the casing string.

Figure 2 is an elevational view of the drilling operation and showing the drill rod and casing advanced through the overburden to bed rock.

Figure 3 is a part-elevational part-sectional view illustrating the next successive step of the drilling operation and showing the locking nut removed from the casing socket and the drill rod string partially removed from the casing.

Figure 4 is a part-elevational part-sectional view of a further step in the drilling operation illustrating the packing nut replaced on the

2

casing connection and the casing extended to the surface and showing the string of drill rod with the driving barrel removed arranged within the casing for freely operating therethrough to advance into the bed rock.

Figure 5 is an enlarged part-elevational part-sectional view showing particularly the casing socket, the drill rod driving barrel fitting within the socket, and locking nut which anchors the driving barrel in interlocked relation with the socket.

Figure 6 is an enlarged perspective view of the casing socket connection and drill rod driving barrel and partially broken away to show the barrel and socket clamped in interlocked relation by the locking nut.

Figure 7 is a view similar to Figure 6 but showing the locking nut removed and the driving barrel separated from its casing socket.

Figure 8 is a vertical mid-sectional view of the bottom end of the casing and drill string showing the relation of the casing bit and diamond bit as the drill and casing are advanced through the overburden.

Figure 9 is a horizontal sectional view taken on the line 9—9 of Figure 1.

In operating diamond drills through overburden which overlays bed rock it is necessary first to sink a casing which will surround the drill rods when drilling into the underlying rock so that the loose boulders, sand and other rubble which make up the overburden will not come in contact with and jam the drill when it is being turned, pulled or lowered.

Under present practices it is conventional to drive a heavy-duty pipe by means of a hammer or driver to sink the pipe to bed rock to form the protecting and guiding casing. In many instances overburden overlays bed rock to a depth of one hundred feet or more and the driving of a heavy duty pipe has its limits due to boulders, gravel or other rubble settling around it and rendering it impossible to be driven any further.

It is therefore imperative that a more positive means of advancing the casing be provided in such circumstances where the pipe cannot be driven through to the bed rock, so that the drill will be fully guided and protected throughout the entire depth of the overburden so prevent binding and breakage of the drill and loss of the diamond-carrying bit.

The present invention completely precludes the possibility of breaking or losing the drill through the overburden by providing a method of establishing with facility a complete casing string

from the bed rock to the surface and of further importance, without requiring any elaborate equipment which would be expensive or difficult to handle in the rough terrain in which the drilling is likely to take place.

With reference to the accompanying drawings, Figures 1 to 4 show progressive steps of my method or operation in sinking the casing below the conventional stand pipe to the bed rock.

Figures 5 to 8 show in detail the special fittings and connections which enable my method to be carried out.

With reference to Figure 1, in carrying out drilling operation methods the first step comprises driving into the overburden 1 a heavy-duty stand pipe 2 as far as it may be driven towards the bed rock or solid rock ledge 3.

Following the driving of the stand pipe it is thoroughly cleaned out and then a string, preferably flush joint casing 4 provided at its bottom end with a casing bit or shoe 5 presenting an annular cutting edge 5', Figure 8, is lowered into the stand pipe to a short distance above the bottom of the stand pipe.

The length of casing required to reach adjacent the bottom of the stand pipe is tabulated. The casing is then cut at a point which will register with the length of a standard number of drill rods 11 which will reach to the bottom of the stand pipe for a purpose which will hereinafter appear. Then to the upper end of the casing 4 is secured by welding a special casing socket member 6, seen particularly in Figures 5, 6 and 7. As will be seen this socket member is formed with inner slots or sockets 7 and with an interiorly threaded upper end portion 8.

With the socket member 6 connected to the top of the casing, the casing is clamped in position in the stand pipe with the connection 6 extending above the top thereof.

Next, the concaved diamond bit 9 is threaded into the short reamer shell or short barrel 10 and started inside the casing member 6. The same number of standard lengths of drill rods 11 as were used with the flush joint casing 4 are screwed together one at a time and lowered inside the casing.

To the top of this string of drill rods 11 is secured a driving barrel 12 which is threaded at its lower end 13 to thread on to the standard drill rod and which is also threaded at its upper end 14 to receive additional lengths of standard drill rod.

As will be seen particularly from Figures 5, 6 and 7, this driving barrel is provided with an annular peripheral flange 15, from the under side of which project the spaced driving lugs 16 which are adapted to be received in the inner slots or sockets 7 of the casing bayonet socket member 6.

As will be seen, the upper portion of the casing member 6 is counterbored at 17 to receive the flange 15 of the driving barrel 12 with the sockets or slots 7 opening at their upper end into the counterbore.

The length of the casing 4 was controlled as previously described so that when the same number of standard lengths of the drill rod are lowered within the casing and the driving barrel inserted to engage its lugs 16 in the sockets 7 the concaved diamond bit 9 will extend a short distance below the casing bit or shoe 5.

With the string of drill rods within the string of casing the special locking nut 18, which is provided with an internally threaded upper end 19 and a reduced externally threaded lower end 20,

is threaded into the upper end 8 of the socket member 6 to securely anchor the driving barrel and casing socket member in interlocked relation, with the end of the nut forcing downwardly on the flange 15 to hold the lugs 16 in their sockets.

Interposed between the end of the nut 18 and the annular barrel flange 15 is a packing ring 21 which serves the very important function of preventing the flow of water-washed cuttings up between the casing and drill rod to jam the driving barrel in the socket member 6 to prevent unlocking of the drill rod string from the casing.

With the various steps described the length of drill rods, with the diamond bit 9 attached at the bottom end and the length of casing 4 with the casing bit 5 attached to the bottom end, are in the position of Figure 1 within the stand pipe. The casing is locked to the drill rod string as explained through the use of the casing socket member 6 and the driving barrel 12 of the drill rod string, so that the casing must rotate and advance with the drill.

After freeing the casing from its clamp, which is not shown as it may be clamped in any manner, the drill rods are tightened in the conventional chuck, which forms no part of this invention and is therefore not shown, and drilling is started. As in the normal drilling procedure water is forced down from a suitable pump through the hollow core of the drill rod string to wash the cuttings up the outside of the drill rod and casing within the stand pipe.

As drilling continues it will be seen that the drill rod string will advance and in advancing will carry the casing string, with the bits 5 and 9 both effecting a cutting which is washed up with the water forced down the drill rod string to cool and cleanse the drill.

Drilling is continued until the casing bit 5 is seated in the bed rock 3, as shown in Figure 2. During the drilling operation the required number of standard lengths of standard drill rod are secured to the threaded upper end 14 of the driving barrel 12 as the drilling proceeds.

After the casing has been advanced down into the bed rock the drill must be freed from the casing so that it can be operated freely and independently to penetrate deeper into the bed rock.

To free the drill from the casing the driving barrel 12 must be removed from the socket casing member 6 and then removed from the drill rod string. To accomplish this part of the operation or method a length of casing 22 is lowered into the stand pipe 2 to reach from the surface to the special locking nut 18. The lower end of this casing is threaded at 23 to thread into the upper end 19 of the nut so that the casing 22 and nut are secured together. The upper end of the nut may be somewhat tapered so that a tight bind is obtainable between the lower threaded end of the casing lengths 22 and the upper threaded end 19 of the nut.

During tightening of this casing length 22 into the nut the packing collar or ring 21 resists further downward movement of the nut into the threaded end of the socket member 6, and after the casing 22 has been secured to the nut, the nut will be threaded out of the casing member 6 upon reverse rotation of the casing 22. Upon removal of the nut the casing 22 and nut are hoisted out of the stand pipe, allowing the driving barrel 12 and the string of drill rod to be removed from the casing, as shown in Figure 3 where the nut is shown wholly without the stand pipe and the drill

rod string with the driving barrel attached partially removed.

Following removal of the drill rod string the casing length 22 carrying the nut 18 at its lower end is lowered back into the stand pipe and the nut is then threaded back into the socket member 6 and a continuous length of casing is established from the bed rock 3 to the surface. A standard core barrel and rods can then be lowered into the casing and drilling through the overburden proceeded with in the usual manner.

In the details of the casing socket member 6 and driving barrel 12, shown in Figures 6 and 7, it will be seen how the locking nut 18 tightly clamps the lugs or prongs 16 of the driving barrel within the socket openings 1 of the casing socket member 6 to securely lock the drill rod and casing together for rotational and longitudinal movement.

Figure 7 also indicates clearly how, upon removing the nut from the casing member 6, the driving barrel 12 can be removed simply and easily from interlocked relation with the casing fitting 6.

The use of the short barrel 10 at the lower end of the drill rod provides greater strength, better fit and wearing qualities than would be the case if the concave bit 9 were fitted to the end of the string of standard rods 11 to facilitate the operation of the drill through the boulder and rubble forming the overburden.

The dimensions of the casing stand pipe and drill rod are of course determined by the size of the drill to be used and the method may be adapted to any drill size.

While the casing and drill rod fittings described and illustrated form the preferred type of interlock between the casing and drill rod, it will be appreciated that other forms of interlocks may be used within the scope of my invention.

The importance of using the simple fittings described will be readily understood for by providing the socket member 6, which will fit with standard casings, and the driving barrel 12, which will fit with the standard drill rod lengths, the whole operation of sinking the casing to bed rock can be carried out simply by adapting the conventional and available drilling equipment. The simplicity of the fittings enables them to be made in situ where any pipe-turning tools are available eliminating delays incident to the procuring of parts. Further, the fittings may be readily handled and transported forming an extremely convenient as well as inexpensive means of enabling my method to be expeditiously carried out.

What I claim as my invention is:

1. In a diamond drilling operation, a method of sinking a casing for guiding and protecting a diamond drill through overburden to bed rock in locations where a stand pipe cannot be driven to penetrate to the bed rock, comprising driving a pipe into the overburden until stopped, lowering a string of casing provided at its lower end with a cutting bit into said pipe to reach adjacent the bottom thereof, attaching a socket fitting to the top of said casing, lowering a string of drill rod provided at its lower end with a diamond bit into said casing to bring the diamond bit below the casing bit, attaching a locking barrel formed with means to interengage with the socket fitting to the upper end of said drill rod string to engage and lock with said casing socket fitting applying a nut to the upper end of said

casing to secure said barrel and socket member in interlocked relation, operating the drill and adding drill rods to said locking barrel to advance said drill and casing locked thereto through the overburden to bed rock adding a string of casing to reach the nut and removing the nut and latter string of casing, then unlocking said driving barrel from said casing socket fitting and removing said barrel from said drill rod, and finally adding to the upper end of said casing string sufficient casing lengths in accordance with the depth to which said casing has been advanced to extend the casing to adjacent the top of said pipe.

2. In a diamond drilling operation, a method of establishing a casing shield through overburden to bed rock in locations where a stand pipe cannot be driven to reach bed rock, comprising driving a pipe into the overburden as far as practical, lowering a string of casing carrying a casing bit at its lower end into said pipe while tabulating the length of casing to reach to adjacent the bottom of said pipe, cutting the casing to correspond to the length of a string of

standard lengths of drill rod to reach adjacent the bottom end of said pipe below said casing bit, securing a socket member to the top of said casing string, lowering a string of drill rod carrying a diamond bit at the lower end into said casing and securing a driving barrel to the top of

said drill rod string to engage and lock with said socket with the drill rod and casing strings relatively positioned whereby the drill rod diamond bit extends slightly below the casing bit, securing a nut on said casing socket member to lock

said barrel in said socket, operating said drill rod while adding the necessary lengths of drill rod and through said drill rod driving barrel operating said casing to advance said drill rod and casing down through the overburden to bed rock, adding casing to reach from the top of said

pipe to said nut and to threadably engage therewith, then removing said nut through said additional casing to release said driving barrel from

said socket member, then removing said drill rod string from said casing to remove said driving barrel, and finally replacing said added casing to extend from the top of the casing string advanced to bed rock to the top of the stand pipe to provide a complete string of casing through the overburden.

3. In a diamond drilling operation, a method of establishing a complete string of casing from the surface to bed rock in locations where a stand pipe cannot be driven to bed rock through the overburden, comprising driving a pipe into the overburden until further progress is blocked, cleaning out said pipe, lowering a string of casing provided with a casing bit at the bottom end to reach adjacent the bottom of said pipe, adding a casing socket connection to the upper end of said casing string, lowering a string of drill rods provided with a diamond bit at the bottom and into said casing to bring said diamond bit below

said casing bit, adding a driving barrel capable of forming a drill rod coupling to the top of said drill rod string, inserting a nut capable of forming a casing connection into said casing socket to lock said driving barrel in said casing socket to lock

said drill rod and casing strings together, operating said drill rod to advance said locked drill and casing strings together to bed rock while adding a sufficient string of drill rod to said driving barrel to reach the top of said pipe as said

drill rod is advanced, lowering an additional

75

string of casing to reach from said nut to the surface and coupling said additional casing to said nut, uncoupling said nut and additional casing by means of said additional casing from said casing socket connection to unlock said driving barrel, removing said nut, additional casing and said drill rod string to remove said driving barrel, and finally replacing said nut and additional casing string to complete the casing from bed rock to the surface.

4. In a diamond drilling operation, a method of sinking a drill rod guide casing through overburden to bed rock in locations where a stand pipe cannot be driven to reach the bed rock, comprising driving a pipe into the overburden until stopped, inserting a casing provided with a casing bit within the pipe, lowering a diamond drill in the form of lengths of drill rods within said casing with the cutting bit of the drill extending below the lower end of said casing bit, locking the drill to said casing for rotation and advancement therewith by means of interengaging drill and casing portions at the upper end of the casing, operating the drill and adding lengths of drill rod to advance the drill and casing to bed rock, then unlocking and removing the drill from the casing, and removing the drill portion adapted to interengage with the casing, then adding to the top of the casing which has been advanced with the drill sufficient casing lengths to extend the casing to adjacent the top of the pipe, re-introducing the drill into the casing and operating the drill with the interengaging portion thereof removed freely within said casing.

5. In a diamond drilling operation, a method of sinking a casing for guiding a drill rod through overburden to bed rock in locations where a stand pipe cannot be driven to penetrate to the bed rock, comprising driving a pipe into the overburden until stopped, lowering into the pipe a casing provided with a casing bit at its lower end and a diamond drill comprising a string of drill rod provided with a diamond bit at the lower end of said drill rod arranged within the casing,

locking the drill and casing together by means of interengaging drill and casing portions at the upper end of the casing with the bit of the drill extending below the bit of the casing, operating the drill to advance the drill and casing through the overburden to bed rock, then unlocking and moving the drill from the casing, and removing the drill portion adapted to interengage with the casing, then re-introducing the drill into the casing to operate freely therewith.

6. Means for locking a string of drill rod to a string of casing, comprising a hollow casing socket member adapted to be secured to a string of casing and formed with at least one socket recess in the inner perimeter thereof and with a threaded upper end, a driving barrel in the form of a hollow tubular drill rod section having upper and lower threaded ends adapted to be secured to drill rod strings and provided with a peripheral lug formation having at least one lug projection to engage in said socket recess, and a nut to engage the threaded upper end of said casing socket member and formed with a lower end to enter said casing socket member and block removal of the lug projection of said driving barrel from said socket recess to lock said barrel to said casing socket member.
